Primary Examiner — George A Bugg*Assistant Examiner* — Jessica A Junkins(74) *Attorney, Agent, or Firm* — Bycer & Marion, PLC; Matthew L. Bycer(57) **CLAIM**

The ornamental design for floating belt bag as shown and described.

DESCRIPTION

FIG. 1 is a top perspective view of a floating belt bag showing my new design;

FIG. 2 is a front view thereof;

FIG. 3 is a rear view thereof;

FIG. 4 is a right side view thereof;

FIG. 5 is a left side view thereof;

FIG. 6 is a top view thereof with strap removed;

FIG. 7 is a bottom view thereof; and,

FIG. 8 is a top view showing the floating belt bag in a position of use with the strap removed.

The broken lines represent the portions of the floating belt bag that form no part of the claimed design.

1 Claim, 6 Drawing Sheets(56)
